UNITED STATES PATENT OFFICE

137,390

DESIGN FOR A HELMET

Harold G. Sydenham, United States Army,
Fort Benning, Ga.

Application April 7, 1943, Serial No. 109,918

Term of patent 14 years

To all whom it may concern:

Be it known that I, H. G. Sydenham, United States Army, a citizen of the United States, residing at Fort Benning, Georgia, have invented a new, original, and ornamental Design for a Helmet, of which the following is a specification, reference being had to the accompanying drawing, forming part thereof.

Fig. 1 is a side elevational view, and
Fig. 2 is a top plan view thereof.

I claim:

The ornamental design for a helmet, as shown.

HAROLD G. SYDENHAM.
